UNITED STATES PATENT OFFICE

2,648,902

HAIR CUTTER

John Petersen, Newark, N. J.

Application July 17, 1951, Serial No. 237,221

1 Claim. (Cl. 30—228)

1

This invention relates to hair cutters and more particularly to an electric motor operated rotary hair cutter.

An object of the invention is to provide a rotary hair cutter, which is relatively simple in construction, light in weight and is of a safety construction so that it may be easily moved over and about the head of a person for cutting their hair without danger of cutting or injuring the person.

Another object of the present invention is to provide a hair cutter as specified, which includes a motor driven rotor having a plurality of straight cutting blades thereon projecting radially from the rotor and lying in a plane parallel to a plane bi-secting the axis of the rotor through their entire length, which rotor cooperates with a stationary cage having a plurality of hair receiving slots therein the edges of which are sharpened to cooperate with the blades to provide cutting of the hair.

With these and other objects in view, as may appear from the accompanying specification, the invention consists of various features of construction and combination of parts, which will be first described in connection with the accompanying drawings, showing a hair cutter of a preferred form embodying the invention, and the features forming the invention will be specifically pointed out in the claim.

In the drawings:

Figure 1 is a longitudinal section through the improved rotary hair cutter.

Figure 2 is a cross section through the hair cutter taken on the line 2—2 of Figure 1.

Figure 3 is a cross section through the hair cutter taken on the line 3—3 of Figure 1.

Figure 4 is a perspective view of the stationary cage.

Figure 5 is a perspective view of the rotor.

Figure 6 is a cross section through the rotor taken on the line 6—6 of Figure 5, and

Figure 7 is a detail view of a fan carried by the rotor for blowing the cut hair out of the cage.

Referring more particularly to the drawings, the hair cutter includes a rotor 1 having a cylindrical core 2 on each end of which are provided stub shafts 3 and 4. The stub shaft 4 is elongated to provide a driving shaft section 5 which is connected by any suitable type of coupling mechanism indicated in dotted lines at 6 in Figure 1 of the drawings to the shaft 7 of an electric motor 8 for rotating the rotor 1. A plurality of cutting blades 9 are carried by the rotor 1, and as shown in Figures 5 and 6

of the drawings two of the blades 9 are provided, being disposed diametrically opposite to each other, extending radially from the core 2 and being straight throughout their entire length. That is, the blades 9 extend throughout their entire length parallel to a plane bi-secting the axis of the rotor 1. It has been the practice in the prior art to spiral the cutting blades so as to provide a shearing action in the cutting of hair but it is extremely difficult, expensive and impractical to make spiral blades of such small size as used in a cutter of this type and, furthermore, sharpening and honing difficulties are encountered with spiral blades, all of which are eliminated by the use of the straight blades which can be easily manufactured, ground and honed on the same type of machines and made in the same manner as various types of safety razor blades.

The rotor 1 is positioned within a cage 10 in the form of a cylindrical shell which is attached in any suitable manner to the electric motor 8 coaxially therewith as clearly shown in Figure 1 of the drawings. The cage 10 has a bearing block 11 mounted in its outer end which is cut away to provide hair escape openings 12 to permit hair to be blown out the end of the cage. A roller or ball bearing 13 is carried by the bearing block 11 and receives the stub shaft 3 of the rotor 1. To prevent longitudinal slippage of the stub shaft 3 in the bearing 13 the stub shaft may be provided with a threaded opening which receives a locking screw 14. The screw 14 threads through the axial portion 15 of the bearing block 11 and clamps the bearing 13 firmly against the end of the core 2 of the rotor.

A second bearing block 16, which is in the form of a disc, is mounted in the opposite end of the cage 10 from the bearing block 11. This bearing block 16 is recessed as shown at 17 to receive the ball or roller bearing 18. A clamping collar 19 is mounted on the shaft 4 and serves to properly space the rotor 1, hold the bearing 18 in place and hold a fan blade structure 20 tightly in position upon the shaft 4 against the shoulder 21 formed on the shaft.

The cage 10 has a plurality of slots 22 cut therein which slots gradually increase in size about the perimeter of the cage as clearly shown in Figure 2 of the drawings. The edges of the slots 22 are sharpened to provide sharpened edges for cooperating with the sharpened edges of the blades 9 to cut hair. To provide the proper shearing action between the cutting edges

of the slots 22 it will be noted that the slots 22 are disposed at an angle relative to a plane or planes bi-secting the axis of the cage so that as the blades 9 are rotated they will progressively sweep across the sharpened edges of the slots 22 to provide the desired shearing action for cutting hair.

The cage 10 has a plurality of notches 24 cut in its end corresponding to the slots 22 and forming indexing means whereby the rotor may be positioned in predetermined relationship to any of the slots. This indexing of the rotor is provided by means of an indexing plate 25 carried by the bearing block 16. The indexing plate 25 has a tongue 26 formed thereon for fitting in any one of the notches 24. A set screw 27 is provided for attaching the indexing plate to the bearing block 16. The bearing block 16 is provided with a plurality of openings 28 extending therethrough. The fan blade 20 is shaped so that during operation of the device it will project a blast of air longitudinally through the cage for blowing the cut hair outwardly through the openings 12.

By disconnecting the coupling 6, removing the cage 10 with its connection with the motor 8 and removal of the screw 14, the cutting parts of the rotary cutter may be easily disassembled for cleaning or sharpening of the cutting blades.

From the foregoing description, taken in connection with the drawings, it will be apparent that a rotary hair cutter has been provided which is practical, comparatively simple in its construction, and one which can be manufactured readily at a comparatively low cost over the type of rotary hair cutters embodying spiral cutting blades and straight hair receiving slots in the cage.

It will be understood that the invention is not to be limited to the specific construction or arrangement of parts shown, but that they may be widely modified within the invention defined by the claim.

What is claimed is:

In a hair cutter, a rotor, means for rotating said rotor, a stationary cage enclosing said rotor, said cage having a plurality of elongated longitudinally extending slots therein and disposed at an acute angle to a plane bi-secting the axis of the cage, a pair of radial diametrically opposed cutting blades carried by said rotor, said blades being straight and parallel throughout their entire lengths to a plane bi-secting the axis of the rotor, the slots in said cage being of different widths and gradually increasing in width from the narrowest slot to the widest slot, and cutting edges at each side of the slots to coact with said blades, means for connecting said cage to a motor, a stub shaft on each end of said rotor, and bearings for said stub shaft carried wholly by said cage.

JOHN PETERSEN.
